UNITED STATES PATENT OFFICE.

HERBERT L. EVANS, OF ST. LOUIS, MISSOURI.

DESIGN FOR A BLANK FOR SHOE-VAMPS.

SPECIFICATION forming part of Design No. 35,544, dated December 31, 1901.

Application filed October 9, 1901. Serial No. 78,111. Term of patent 7 years.

To all whom it may concern:

Be it known that I, HERBERT L. EVANS, a citizen of the United States, residing at St. Louis, Missouri, have invented a new and original Design for a Blank for a Shoe-Vamp, of which the following is a specification.

This invention comprises a vamp for a shoe formed of one piece and having a new and original shape or form.

5 The blank comprises a single strip having two correspondingly-shaped members connected by an integral rounded central portion, the ends of the members being wider than the major portion of the blank.

5 The blank is illustrated in the accompanying drawing, in which the view represents the article in plan.

As will be seen from the drawing, the blank

is formed of a single piece having correspondingly-shaped members *a a*, connected by an integral rounded portion *b*, toward which the portions *b' b'* of the members *a a*, which are of uniform width throughout, converge from the points *c c*. From the latter point the rear end portions *c' c'* of the members *a a* extend, increasing gradually in width from said points *c c* to the termination of said end portions *c' c'*.

I claim—

The design for a blank for a shoe-vamp as herein shown and described.

HERBERT L. EVANS.
